Patented Aug. 10, 1920.

Inventor:
Ira L. French

UNITED STATES PATENT OFFICE.

IRA L. FRENCH, OF CHICAGO, ILLINOIS, ASSIGNOR TO THE MANTLE LAMP COMPANY OF AMERICA, OF CHICAGO, ILLINOIS.

DESIGN FOR A HEAT-INSULATED RECEPTACLE.

56,061.

Specification for Design.

Patented Aug. 10, 1920.

Application filed October 29, 1919. Serial No. 334,366. Term of patent 14 years.

To all whom it may concern:

Be it known that I, IRA L. FRENCH, a citizen of the United States, residing at Chicago, in the county of Cook and State of Illinois, have invented a new, original, and ornamental Design for Heat-Insulated Receptacles, of which the following is a specification, reference being had to the accompanying drawing, forming part thereof.

The figure is a view in elevation of the receptacle.

This receptacle is circular in cross section and is distinguished by having circumscribing dark stripes of considerable width, between and above and below which are circumscribing proximate ribs. The upper and the lower ribs may be triplicated, as shown.

The intervening ribs may also be triplicated, and they may, furthermore, be associated with other ribs from which they are slightly separated.

The receptacle is bulged at the center and terminates in a contracted neck carrying a cap or closure. As shown, the vessel may be provided with a bail. The principal features of the design are the alternating stripes and plural ribs arranged to ornament a receptacle of the general type illustrated in the drawing.

I claim:

The ornamental design for a heat-insulated receptacle, as shown.

In testimony whereof I affix my signature.

IRA L. FRENCH.
